UNITED STATES PATENT OFFICE.

EUGENE ROBERTS, OF SALT LAKE CITY, UTAH, ASSIGNOR TO THE WESTERN STATES MACHINE COMPANY, OF SALT LAKE CITY, UTAH, A CORPORATION OF UTAH.

CENTRIFUGAL MACHINE.

Application filed July 30, 1920. Serial No. 400,119.

To all whom it may concern:

Be it known that I, EUGENE ROBERTS, a citizen of the United States, and resident of Salt Lake City, in the county of Salt Lake and State of Utah, have invented certain new and useful Improvements in Centrifugal Machines, of which the following is a specification.

In separating solid matter from a liquid body by centrifugal force as in the case of extracting sugar from the raw juice or from syrup, it is common practice to cleanse or wash the solid matter walled up on the interior of the basket by directing a spray of washing liquid or water against the solid matter or sugar while the machine is still rotating. It is also desirable that the washing liquid shall not be mingled with the juice or liquid content that has just been separated centrifugally from the sugar.

The present invention is intended to provide a simple and convenient construction by which such separate collecting of the two liquids separated from the sugar by successive operations may be easily and reliably effected. A further object of this invention is to render impossible the mingling of the two different extracted liquids through any carelessness or oversight on the part of the attendant, since obviously if the attendant should fail to adjust the deflecting plates after the raw juice is extracted before starting the washing operation, the washing liquid would be mingled with the cane juice even though appliances are provided to prevent this. To avoid the consequences of such oversight the deflector plates or shutters are automatically returned to or maintained in operative closed relation to one collecting trough or ring and are automatically shifted to open position through suitable connection with the washing apparatus, so that as the washing apparatus is started in action the shutters are open to deflect the centrifugally separated liquid into the other collecting trough.

Means are also provided by which the shutter closing means are prevented from acting simultaneous with the return of the washing control mechanism to normal position, such means being preferably correlated with the pivotal discharger shaft so as to be released when the discharger shaft is turned to bring the discharger plow into action, it being understood by those skilled

in the art that the discharger plow is brought into action after the washing operation by swinging the plow on its main pivotal shaft or standard.

In illustrating this invention only such parts of the washing apparatus and of the discharger device are shown as is necessary to an understanding of the present invention. It may be stated, however, that the shaft of the discharger device herein shown corresponds to the main supporting shaft shown in letters patent of the United States issued to Roberts and Gibson Dec. 12, 1911, No. 1,011,851. The sugar washing apparatus forms no part of the present invention but is of the general type shown in Roberts and Gibson Patent 1,224,095 dated April 24, 1917. It will also be understood that while the illustration of the present invention includes the constructions referred to in the said co-pending application and in the said patents mentioned, the invention is not restricted in its application to the utilization of such specific structures but in this particular is based upon the principle of correlating the movement of the shutters, by which separate collection of the two different separated liquids is effected, with the washing apparatus, so that the washing operation will not begin in advance of the proper shifting of the deflecting shutters. Moreover, the automatic control of this shutter movement is also considered to be an important feature of the invention.

In the accompanying drawings I have illustrated the preferred construction and arrangement embodying the principles of this invention in which—

Figure 1 is a vertical elevation chiefly in cross section showing the arrangement of the movable shutters or deflector plates and the mechanism by which they are operated in combination with the washing mechanism.

Figure 2 is a plan view in section showing the overlapped relation of the shutters and hinged support therefor.

Figure 3 is a plan view partly in horizontal section showing the relation of the automatically acting bail to the shutter closing devices.

Figure 4 is a side elevation showing the connections between the shutter mechanism, the washing apparatus and the discharger shaft.

Figure 5 is an enlarged detail view show-

ing the interlocking clutch connection between the starting spindle of the washing apparatus and the actuating lever for opening the shutters.

5 Figure 6 is an end view of the clutch member splined to the starting spindle of the washing apparatus.

Figure 7 is an endwise view of the cooperating face of the actuating lever hub forming 10 the other member of the clutch.

According to the usual practice, I provide a stationary curb or casing 1 which surrounds the usual centrifugal basket which is omitted from the drawing to more 15 clearly show the pertinent parts of this invention. This curb, however, at its bottom is provided with two collecting troughs or rings 2 and 3 concentric with the central opening of the curb through which the 20 sugar is discharged out of the basket after each separating and washing operation.

Inside the curb in a position to lie outside of the centrifugal basket are mounted a series of cylindrically curved segment plates 25 4 and 5 each of which preferably extends through an arc of approximately 90° so that the four vertical cylindrically curved plates form a cylindrical wall interposed between the outside of the centrifugal basket and the 30 inside of the curb. Each plate is provided near its top with a pair of perforated ears 6 which are mounted astride of an inwardly projecting lug or bracket 7 secured to the curb near the top thereof so as to afford a 35 hinged joint for each of said plates upon the pivot pin 8 which is passed through the aligned perforations of the hinged members.

By offsetting the pivotal joint to the outside of the vertical line of each hinged plate 40 or shutter there will be a tendency of the bottom of the plates to swing outward owing to gravity thus dispensing with the use of any spring to cause this outward movement of the shutter.

45 The shutter plates are so formed that when in innermost or closed position their lower ends rest snugly against the partition ring 9 which separates the outer from the inner trough and they also have their vertical edges in close contact so as to prevent the outwardly thrown liquid from the basket from passing into the space outside of the vertical plane of the partition ring 9. When in this innermost or closed position 50 therefore, the liquid thrown out against the interior surfaces of the shutters is directed into the inner ring 3 whence it is carried off into a suitable storage receptacle.

When, however, the shutters are opened 60 or swung outwardly on their hinges the centrifugally expelled liquid impinges against the shutters and runs down into the outer trough 2 whence it is conducted to a separate storage receptacle.

65 The apparatus shown in the draw-

ings works upon the principle of providing means for normally maintaining the shutters in their innermost or closed position and of returning them automatically to such closed position when released from their expanded 70 or opened position. Any suitable mechanism may be employed for securing this action but I have herein shown a rotary sleeve or cam member 10 mounted in a bearing bracket 11 fixed to the outside of the 75 curb there being a corresponding bearing bracket and cam sleeve on the diametrically opposite side of the curb, as shown in Figures 1 and 3. On the outside of the two opposed shutter plates 4 is mounted a hook- 80 like member 12 which engages a cooperating cam member 13 having a stem 14 extending inside of the hollow cam member 10 for bearing support. The hook 12 prevents the cam member 13 from turning on 85 its axle against the rotative thrust of the cam member 10, and it will be seen by reference to Figure 3 that when the cam member 10 is turned in one direction its oblique cam surface rides against the oblique cam 90 surface of the cooperating cam member 13 thereby forcing the cam member 13 and the plate 4 inwardly toward the center which results in establishing a close contact between the lower ends of the plates 4 and 95 the partition ring 9.

For effecting this inward movement automatically I provide a hub or sleeve 15 on the outer end of each rotative cam member 10 and secure to said sleeves an approximately semi-cylindrical bail 16 carrying a weight 17 which normally tends to depress the bail and consequently to rotate the closing cam members 10 in a direction to push inwardly the pivotal plates 4. As 100 shown in Figure 3 the oblique surface of the closing cam 10 may be formed to ride by the oblique surface of its cooperating member 13 so as to form a positive lock for supporting the shutters 4 in their closed position.

The intermediate opposed shutters 5 are so connected with the shutters 4 that the inward and outward movements of shutters 4 result in the corresponding movement of 115 the intermediate shutters 5. This movement is effected by any suitable connection but I have here shown in Figure 3 the plates 4 provided with circumferentially extended tongues or strips 18 which overlap the vertical joints or edges of each pair of adjacent plates, the plates 5 being provided with straps 19 through the inside of which these overlapping strips or tongues are passed so as to permit the tongue 18 to slide circumferentially on the plate 5 while retaining operative connection therewith through the straps or other holding means 19. By means of such connections it will be seen that when the plates 4 are forced inwardly 120 130

this inward motion is transmitted through the interlocking tongues 18 to the intermediate segment plates 5. On the other hand, the outward movement of the four plates is 5 made uniform through the same connection whereby all four plates are either contracted or closed or expanded or opened in like degree and simultaneously.

As I have previously indicated to make 10 the device proof against oversight on the part of the operator it is desirable that when the washing operation begins the shutters should be expanded or opened so as to deflect the washing fluid into the outer trough 2, the inner collecting trough 3 being used 15 to collect the raw juice from the sugar or other material that is being treated. With this object in view, therefore, I have so interconnected the washing apparatus with the 20 shutter controlling devices that the washing operation can not start unless the shutters are expanded or opened.

In view of the fact that the particular 25 washing apparatus forms the subject matter of my co-pending application mentioned above I will explain only such parts of this mechanism as are directly concerned with the present invention. For general purposes it will suffice to state that the washing 30 apparatus comprises an oscillating spray nozzle 20 and a valve controlling mechanism operated from a driving pulley 21 when the rock-shaft or starting spindle 22 is partially rotated in a contra-clockwise direction having 35 reference to Figure 4.

On the end of the starting spindle or rock-shaft 22 of the washer is mounted a pivotal 40 arm 24 whose hub 24^a is free to rotate about the axis of the shaft. As shown in Figure 45 5 a fixed sleeve 30 is secured to the casing 23 and projects through the hub 24 with its outer edge scalloped to form an endwise thrust stationary cam for purposes presently to be described.

On the outer end of the spindle 22 is slid- 50 ingly splined a clutch member 31 having a projecting tooth 32 normally interlocked rotatively with a corresponding projecting tooth 29 on the end of the hub 24^a. A spring 55 33 thrusting against a nut 34 on the end of the spindle serves to keep the splined clutch member 31 pressed normally into interlocking engagement with the hub 24^a and against the scalloped end edge of the sleeve 30. The 60 object of this construction is to cause the lever 24 when moving in a contra-clockwise direction to turn the starting spindle 22 through a sufficient arc to cause the washing mechanism to begin its operation and then 65 allow the interconnected lever 28 of the shutter controlling mechanism to remain in shutter opening position while the spindle 22 and the clutch member 31 return to their initial or idle position as soon as the wash- 70 ing operation is completed.

A starting arm or lever 28 is secured to the bail-carrying hub or sleeve 15 which is attached to the locking cam 10 so that the throw of the shifting lever 28 to the right (Fig. 4) acts to release the interlocking engagement of the two cam members 10, 13 and allow the shutters or partition sections to swing outwardly in position to deflect the washing fluid into the outer trough 2.

The starting lever 28 is pivotally connected with a link 27 having a slot 26 to receive a pin or roller 25 projecting from the end of the rock-shaft 24. Consequently, as the arm 28 is thrust to the right to the position indicated by dotted lines in Figure 4, as soon as the outer end of the slot 26 begins to pull against the pin 25, it causes the partial rotation of the starting spindle 22 of the washer, so that at the same time that the deflector plates are shifted to operative 85 relation to the outer ring the automatic washing apparatus is set in operation. In other words the lever 28 performs the two-fold function of shifting the shutters of the sectional partition to their outermost position to deflect the washing liquid into the outer trough and at the same time it causes the washing apparatus to be set in operation through the rotation of its starting spindle. The slot 26 is employed to compensate for the difference in length of the levers 28 and 24 since in order to shift the deflector plates or shutters the lever 24 must have considerably greater movement than is required to shift the starting arm 24 of the 100 washer from inoperative to operative position.

Since it would not be desirable to have the deflector or shutters of the curb shifted from their outermost position just as soon as the washing spray is cut off, since there will be some washing liquid still in the sugar that needs to be extracted, I provide a latch 40 having a hook 41 engaging a catch plate 42 and pivotally connected with 110 arm 28 so that when the arm 28 is swung to the right the hook latch will catch against the stop member 42 and retain the shifting lever in such operative relation against the weight of the bail until the operator is 115 ready to discharge the sugar which is the next step in handling the material.

In order that no separate attention on the part of the operator may be required I prefer to make provision for disengaging the 120 latch 40 from the stop member 42 by movement of the main discharger shaft 43 which is necessary to bring the discharger plow into action. With this object in view I bevel the front end of the latch 40 as shown 125 at 44 and locate a projection or pin 45 on the discharger shaft 43 so that as the discharger shaft is rotated to operative position for using the discharger, the projecting pin 45 rides against the bevel 44 and 130

lifts the latch so as to disengage it from the stop member 42 in which position the weight bail is free to return the arm 48 and the shutters 4 and 5 to their normal or initial position ready for treating the next charge of sugar in the machine. The discharger is of the general type illustrated in U. S. Patent 1,011,851 December 12, 1911 in which the discharger plow is swung on its pivotal axis toward and away from the wall of the basket, and as this is an old construction only the plow-supporting rotatable post 43, which carries the release pin 45 is illustrated in the drawings.

15 It will, therefore, be seen that the three successive operations, namely, of extracting the juice, washing the sugar and discharging the sugar are so interconnected or correlated by means of this apparatus that the 20 deflecting shutters are normally in proper position to deflect the juice into its collecting trough during the first operation and to shift the deflecting shutters to operative relation to the ring that collects the washing 25 fluid at the same time that the washing apparatus is set in motion, and further that the deflecting shutters remain in this latter position for properly deflecting the washing fluid until the attendant is ready to operate 30 the discharger for the purpose of unloading the material. In this way the separation of the two different centrifugally separated liquids is effected without liability to error, the whole being automatically effected by 35 merely shifting the arm 28 and performing the necessary movement to operate the discharger whenever the operator is ready to do so.

40 The four arcuate pivotally mounted deflecting plates being interlocked must move inward and outward simultaneously. When the hand lever 28 is in vertical position shown in Figure 4 these deflectors are in their innermost position thereby serving to 45 direct the cylindrically extracted juice into the inner ring 3. Upon throwing over the lever to start the washer or sprayer all deflector plates are thrown outwardly into position to guide the washing liquid into the 50 outer collecting ring 2 and are automatically locked in that position by means of the hook latch 40. When the washing period is concluded and it then becomes necessary to discharge the sugar, the turning of 55 the discharger post 43 into position to bring the discharger plow into action in accordance with the well known practice, serves to release the latch 41 by the lifting engagement of the pin 45 on the discharger post 60 so that the weighted arm 16 automatically restores the deflector plates to their inward position ready to deflect the extracted juice from the next charge treated in the machine 65 into the appropriate inner ring. While the device can be operated at will by the attend-

ant, yet the automatic operation renders it fool-proof against neglect or oversight.

What I claim is:

1. In a centrifugal machine the combination of a curb or juice collecting casing provided at its bottom with outer and inner collecting troughs having separate outlets, an interior movable partition subdivided vertically into curved sections or shutters supported to form a circular shield for deflecting the centrifugally expelled juice into the inner trough and being movable outwardly away from said inner trough into position to deflect centrifugally expelled liquid into the outer trough, and means for normally retaining said sections or shutters into their inmost position during the operation of extracting the liquid content from the material that is centrifugally treated, substantially as described. 85

2. In a centrifugal machine, the combination of a basket inclosing casing provided with inner and outer collecting troughs, an interiorly disposed partition comprising curved sections mounted to swing on horizontal pivots so as to be adjustable into deflecting relation to either one of said troughs, and means for effecting corresponding adjustment of said sections in order to deflect centrifugally separated liquids into their appropriate troughs substantially as described. 90

3. In a centrifugal machine, the combination of a basket encircling casing provided with two concentric troughs, an interiorly disposed partition wall comprising curved sections mounted above said troughs to permit movement of their lower ends away from the inner trough toward the periphery of the outer trough and means for shifting said sections to direct the flow of centrifugally separated liquids to the appropriate trough, substantially as described. 100

4. In a centrifugal machine, the combination of a basket inclosing casing, an interiorly disposed partition wall comprising curved sections having contacting vertical edges movable toward and away from the centre of the casing, shifting cams having operative engagement with the exterior faces of said sections to move them inwardly from their outermost position, said casing being provided at its bottom portion with outer and inner liquid collecting troughs arranged respectively to receive the liquid thrown against said partition when the sections are in their different positions of adjustment, substantially as described. 110 115 120

5. In a centrifugal machine, the combination of a basket encircling casing provided at its bottom with an annular liquid collecting trough, an annular partition subdividing said annular troughs into two separate collecting troughs, a circular partition mounted above said trough comprising 125 130

- ing curved sections movable into close contact with said annular partition to direct the liquid thrown against said sections into the inner trough, and movable outwardly away from said partition to direct the liquid into the center trough and means for simultaneously shifting said sections into operative deflecting relation to one of said troughs, substantially as described.
6. In a centrifugal machine, the combination with an automatic washing apparatus, a basket inclosing casing, provided with outer and inner liquid collecting troughs, means for deflecting the centrifugally separated liquids into either of said troughs, means for controlling the position of said deflecting means, said controlling means being interconnected with the washing apparatus whereby the shifting of the controlling means to a predetermined position results in setting in operation the washing apparatus, substantially as described.
7. In a centrifugal machine, the combination of a washing apparatus for washing the solid matter retained in the centrifugal, a basket inclosing casing provided with separate liquid receiving troughs, means for deflecting the centrifugally separated liquid into either trough, a lever having connection with said washing apparatus to start its operation and having also operative connection with said deflecting means to shift the deflecting means into position to direct the centrifugally expelled washing liquid into its appropriate trough, substantially as described.
8. In a centrifugal machine the combination of a basket encircling casing provided with separate receptacles for centrifugally expelled liquids, means for deflecting the expelled liquid into either of said troughs at will, a washing apparatus located to spray the solid matter in the centrifugal, a lever for setting said washing apparatus in operation said lever having operative connections to shift the deflecting means into position to direct the centrifugally expelled washing liquid into its appropriate receptacle, and means for retaining said lever in such shifting position after the washing apparatus has ceased to operate, substantially as described.
9. In a centrifugal machine, the combination of a basket-inclosing casing interiorly disposed deflecting means arranged within the casing and shiftable into position to direct centrifugally expelled liquids into separate receptacles in the casing, an automatic washing apparatus, a discharger device for removing the solid matter from the centrifugal after the liquid extracting and washing operation, a lever interconnected with both the washing apparatus and the deflecting means, said lever acting when shifted to operative position to start the washing apparatus and to shift the deflecting means to position for directing the centrifugally expelled washing fluid into its appropriate receptacle, and means for retaining said lever in operative position, after the washing apparatus has completed its cycle, said retaining means being automatically released to restore the deflecting means to normal position by the discharger shaft as the latter is moved into operative discharging position, substantially as described.
10. In a centrifugal machine, the combination of a basket-inclosing casing, interior deflecting means for directing centrifugally expelled liquids into different receptacles, a washing apparatus, a discharger device, a deflector controlling member interconnected with the washing apparatus and the discharger shaft to start the washing device in operation when the deflecting means is shifted to appropriate position, and for releasing the deflecting means to allow its return to normal position when the discharger shaft is turned to put the discharger into action, substantially as described.
11. In a centrifugal machine, the combination of basket-inclosing casing, provided with separate collecting troughs, deflecting means for directing centrifugally expelled liquids into either trough according to the position of adjustment of the deflecting means, automatic sugar washing apparatus having a starting member by which it is set in operation for a predetermined period, a lever acting when moved to operative position to shift the deflecting means to operative relation to the trough for collecting the washing liquid, a link connecting said lever with the starting member of the washer, and means for retaining the lever in its operative position when the starting member of the washer has returned to normal position, substantially as described.
12. In a centrifugal machine, the combination of a basket inclosing casing, provided with separate collecting troughs, deflecting means for directing centrifugally expelled liquids into either trough according to the position of adjustment of the deflecting means, automatic sugar washing apparatus having a starting member by which it is set in operation for a predetermined period, a lever acting when moved to operative position to shift the deflecting means to operative relation to the trough for collecting the washing liquid, a link connecting said lever with the starting member of the washer, a detent for retaining the said lever in its operative position after the washing apparatus has completed its cycle, and means for automatically releasing said detent when the discharger is moved into operative position, substantially as described.
13. In a centrifugal machine, the combination of a basket encircling casing, an in-

- terior sectional deflecting wall shiftable into position to direct centrifugally expelled liquids into separate receptacles, a lever for shifting the said sectional wall from one 5 position to the other, washing apparatus for washing the solid content in the centrifugal, means connecting said lever with the starting member of said washing apparatus in order to set the washing apparatus in operation when the lever is shifted said connecting means being automatically disconnected with the starting member when the starting member is shifted to operative position, substantially as described.
15. 14. In a centrifugal machine, the combination of an encircling sectional deflector wall

arranged to surround the centrifugal basket and shiftable into different positions to direct the centrifugally separated liquids into different receptacles, a lever for effecting 20 said shifting movement, a washing apparatus, means interconnecting said lever with the starting member of said washing apparatus said means embracing a clutch formed to automatically disengage itself 25 from operative connection with said starting member in order to allow said starting member to return to normal position without resetting said lever, substantially as described.

In witness whereof, I have subscribed the 30 above specification:

EUGENE ROBERTS.
